UNITED STATES PATENT OFFICE.

HOWARD CONSTABLE, OF NEW YORK, N. Y.

FIREPROOF CONSTRUCTION.

SPECIFICATION forming part of Letters Patent No. 642,208, dated January 30, 1900.

Application filed August 21, 1897. Serial No. 649,015. (No model.)

To all whom it may concern:

Be it known that I, HOWARD CONSTABLE, engineer and architect, of 22 East Sixteenth street, in the city of New York, State of New York, have invented certain new and useful Improvements in Fireproof Constructions, of which the following is a description, referring to the accompanying drawings, forming part of this specification.

10 My invention particularly concerns fire-proof construction for floors, roofs, and structures subjected to serve transverse strains.

Briefly stated, it consists in means for supporting the load in an economical manner 15 and at the same time protecting the load-supporting portions of the floor from fire, water, and other destructive action in such a manner that when the protective portion of the floor has been injured or broken away it may 20 be repaired in a highly-economical way and without affecting or requiring the renewal of any part of the load-sustaining portion of the floor. In addition to this my invention contemplates certain improvements in the 25 details of the load-sustaining portion of the floor and improvements in floor construction generally, which will be fully apparent from the accompanying description and claims.

In the accompanying drawings, Figures 1, 30 2, and 3 are diagrammatic plan views illustrating well-known details in floor construction. Fig. 4 is a section of a well-known form of floor transverse to the I-beams. Fig. 5 shows another known type of floor transverse 35 to the I-beams. Fig. 6 shows part of my invention as applied to floors of the type somewhat similar to that shown in Fig. 4. Figs. 7 and 8 are sections transverse to the I-beam and parallel with the I-beam of a so-called 40 "flat-arch" floor embodying part of my invention. Figs. 9 and 10 are similar views of a modification. Fig. 11 shows another modification. Figs. 12 and 13 show my invention as applied to floors which do not have a flat ceiling. Fig. 14 shows further modifications. Fig. 15 shows in section transverse to the I-beam a half-span of a floor embodying in one 45 approved form all the features of my invention. Fig. 16 is a cross-section of the same 50 on the plan 17 17 of Fig. 15. Figs. 17 and 18 show details of my fitting-piece, by which floors may be fitted in place accurately not-

withstanding variations in the distance between beams and in the other dimensions of the floor.

Throughout the drawings and specification like letters of reference indicate similar parts.

It will be convenient first to arrive at a clear meaning of the terms which I shall make use of in explaining my invention and also to understand the present state of the art, which I seek to radically improve.

The "main supports" are the walls, trusses, and girders or beams, (diagrammatically represented by the lines *a b*, *b c*, *c d*, *d a* in Figs. 65 1, 2, and 3.)

"Secondary supports" are beams, bars, cables, arch-ribs, expanded metal, wire-mesh, and the like, transferring the weight of the floor and the supported load to the main supports.

The secondary supports are usually placed at intervals, either parallel with each other, as diagrammatically indicated by the lines in Fig. 1 or *g h* in Fig. 2, or placed in a variety of ways—such, for instance, as indicated at Fig. 3 by the lines *j l*, *k l*, and *j k* in Fig. 3.

In some floors, especially when the main supports are not too far distant from each other, the secondary supports may be omitted entirely, in which case the main supports fulfil the same relation to the "load-

supporting body" of the floor as do the secondary supports when such are present—that is to say, the secondary supports may be considered as subdividing the floor into smaller 85 areas. The term "supports," therefore, when not qualified covers either the main supports or the secondary supports when such are present.

The "load-supporting body" or "load-sustaining portion" of the floor forms the main 90 body of the floor and transmits its own weight and the weight of the load either directly onto the main supports or to the secondary supports and thence to the main supports when secondary supports are present. This load-

supporting body in well-known forms consists variously of lintels containing hollow spaces, metal arch-plates, ribs, or rods, expanded metal, wire-mesh, trusses, simple or combined "flat arches," and a variety of combinations 100 of tile-cement and concrete with suspension-rods, tie-rods, and other elements. In the load-supporting body, therefore, hollows or air-spaces may exist with advantage.

The "floor-filling" is material which is used mainly for the purpose of filling in hollows in the load-supporting body either for the purpose of increasing the fire resistance or deadening sound or increasing the massiveness of the structure where massiveness is desired. For this purpose ashes, cinder, concrete, and a variety of other materials have been used, and the filling is frequently made a combined part of the load-sustaining body, serving the dual function of filling in space and adding to the strength.

The "flooring" is the portion either superposed or combined with the load-supporting body to form a wooden, cement, tile, or other floor - surface. This includes frequently wooden sleepers embedded in the upper portion of the load-sustaining body for the purpose of securing a finished wooden surface or for providing nailing-strips for carpets. "Flange protection" or "I-beam protection" is the means usually employed in the form of small tiles or of other refractory material placed directly beneath the lower flange of the I-beams or other iron-work to retard the action of heat upon the iron-work in case of fire.

The "ceiling construction," "ceiling," or "ceiling-finish" is the under-surfacing of the structure for appearance—plastering, either white or tinted or painted or papered, is usual. Ornamental tile, sheet metal, wood, and a variety of other finishes are of course familiar variations.

In the figures I have indicated the load-supporting body by the letters *l* and *l'*, using *l'* to indicate the iron members or elements of the load-supporting body. In Fig. 5 the iron member *l'* is an arch-plate. In Fig. 12 a tension-rod or suspension-rod is embedded in the concrete body. In Fig. 16 the iron member *l'* is both a suspension-rod and a tension member of a compound truss or girder *r*, as will be explained more in detail. In Figs. 4, 6, 7, 8, 9, 10, 11, 13, and 14 tile constructions are shown, and in Figs. 5 and 12 concrete constructions are shown. The filling is shown at *m m'*, *m* indicating concrete or other filling, which forms also part of the load-sustaining body, and *m'* filling which is not a substantial part of the load-sustaining body, though it incidentally contributes somewhat to the strength and rigidity of the structure. The filling *m'*, if of sufficiently good material, may also constitute to a large extent the finished floor-surface, no separate flooring as such being then used. In Figs. 5 and 12 I have shown a cement flooring *o*, and in Fig. 15 wooden sleepers *o'* for securing a wooden floor or other facing.

In modern fireproof construction great pains have been taken to make the load-sustaining body of the floor fireproof, and the fireproofing elements are usually inseparably combined in and with the load-supporting body of the floor, though in some cases separated by air-spaces from the upper parts

thereof. In case of damage by fire and water the load-sustaining body of the floor has to be entirely rebuilt or extensively repaired before it can be put in proper shape. One part of the present invention consists in entirely divorcing the load-sustaining body and the fire and water resisting elements in such a way that the fire and water resisting elements when damaged or when torn from the floor by the physical and mechanical action of the powerful and suddenly-cooling stream of water from the fire-engine may be separated from the load-sustaining body without the least injury to the load-sustaining body. The ordinary method of extinguishing fires by water under a pressure of twenty-five to two hundred pounds to the square inch and in a stream of considerable volume issuing at great velocity is extremely violent, both as a mechanical force in tearing away the lighter portions of the metal-work and the fireproof materials and in its physical and chemical effects. The sudden chilling of the metal-work in the floor causes warping, twisting, and violent strain of the structure, frequently requiring its complete reconstruction after the fire is out and in the case of extensive fires causing the entire collapse of the load-sustaining body and frequently of the I-beams or other secondary supports. The water, moreover, meeting the heated iron exerts a powerful and exceedingly-destructive corrosive action, which is greatly facilitated by the cracking, disintegration, and falling away of the lower portions of the large tiles and cement surfaces common in floors. Light-wire netting, expanded metal, or thin plates are practically destroyed by this action, because the scale of rust so formed is a large percentage of the thickness of light-wire rods or sheets, so that the load-supporting body, if it does not entirely fall through, has to be entirely replaced. By extensive inquiry concerning damage by fire and water in the large cities in this country I have discovered that the so-called "fire-proof" materials, such as large bodies of dense tile and the like, while poor conductors of heat and entirely incombustible, are, nevertheless, exceedingly-poor water-resistors. The large hollow tile blocks, heretofore classed as the best form of fire-resisting floor construction, are by no means best for resisting combined fire and water, to which they are alternately subjected by the flames and the upwardly-impinging water stream. I have discovered that small and solid forms of tile, preferably porous tile, will resist the action of fire and water in a different and far better manner, probably because less opportunity is given for the disruptive expanding and contracting strains than in the case of large hollow tiles. The ordinary plastering, consisting of several coats of combinations of lime, sand, hair, and plaster-of-paris, is only a moderate heat-resister and a very poor water-resister indeed. The lime and plaster-of-paris are calcined or disintegrated and the

hair destroyed where it is present at comparatively low temperature. Tests witnessed by the New York Building Department have shown that the plastering usually falls off 5 soon after being subjected to the fire and even before water is used, which confirms the statement that it should be considered as a ceiling-finish and not a fire and water protection to the floor construction. A temperature of 10 2,500° is not unusual in fires within so-called "fireproof" buildings, and at a temperature as low as 1,000° iron and steel become soft. Brick, terra-cotta, and the like, which are manufactured at temperatures of from 2,000° 15 upward and are called "burnt" materials, are therefore, as far as I am aware, the only materials used in fireproof construction which resist excessive temperatures, and in this specification I desire to distinguish these 20 from cements, concretes, and other materials "set up" in a plastic state and allowed to harden without burning; but these two kinds of materials compare in economy in an entirely different way, since the cements and 25 concretes are economical and far cheaper than the terra-cotta, brick, and burnt materials, since they can be fitted and used without wasteful and extensive cutting and fitting.

In my improved construction I embody a 30 load-supporting structure in which no burnt materials whatever need be employed. Between this load-sustaining structure and the ceiling and detachably secured to the load-supporting body I introduce a layer of non- 35 corrosive and great fire and water resisting material, the said layer being secured by cement, plaster, or the like to the load-supporting body by surfaces or points of contact for fracture, cleavage, or divorce between itself 40 and the load-supporting body. The surface or point of contact for fracture, cleavage, or divorce is the cement or plaster joint or other fastening device by which the intermediate layer is secured to the load-supporting body 45 and is sustained by the load-supporting body during or after damage by fire. By this means I am able to combine in a floor a relatively-cheap load-supporting body which is excellent in point of strength, but not of the highest 50 fire-resisting quality, with a separate and distinct fire and water resisting body or layer of relatively-greater fire and water resisting capacity detachably formed or detachably secured beneath the load-supporting body in 55 such a manner that if it shrinks, warps, or contracts it will not affect the load-sustaining portion of the floor and is capable of being entirely detached and replaced after the fire is over. I am thus enabled to combine 60 for the first time a floor in which the load is supported in the most economical manner without regard to the fire-resisting qualities, and at the same time I produce the highest 65 protection against the corrosive and destructive action of fire and water and in addition to all this secure the greatest possible economy in repairing the damage which almost

inevitably must result from fire and water. In its broader aspects the load-supporting body may be of any type desired; but in the 70 form which at present seems to be most advantageous cement, concrete, or other set-up material will form the larger portion of the load-supporting body.

In the drawings I have illustrated the ceiling at *y* and my fire and water resisting portion at *x*. In Figs. 9, 10, 11, and 15 I have shown a finished tile ceiling. In the other figures I have shown the usual plaster ceiling. My intermediate layer must not be confounded with a finished or ornamental tile ceiling, because the latter is not interposed in any sense between the ceiling-finish and the structure, but forms in itself the ceiling-surface directly exposed to the flames and 85 the action of water. It will be seen that my fire-resisting detachable layer, as shown in the figures at *x* and as there indicated preferably, though not necessarily, consisting of somewhat thick and preferably porous tile 90 blocks of small area, is not exposed to the direct action of the flames until after the ceiling-finish has been disintegrated or removed by the fire and water and that then, though in some cases the protective layer may even 95 become partially fused, it checks the progress of the fire and the destructive action of the fire and water and protects the floor construction proper—that is to say, the load-supporting 100 body of the floor.

My preferred construction, which embodies also certain other parts of my invention that contribute to the formation of a more perfect floor, is shown in Figs. 15, 16, 17, and 18. In Figs. 15 and 16 the load-supporting body 105 consists of a series of blocks *r*, which may with advantage be arched, as shown, and of the cross-section plainly indicated in Fig. 16. These may be made of cement or other material at the factory and transported ready to be 110 set in place between the beams without the use of centers. They may vary considerably from the type shown in the figures, though preferably they will be formed of the strong upper and lower portions and the lighter and preferably open-work web. They are cut away 115 to extend above the flange of the I-beam and present a lower horizontal bearing or surface *s*, which may rest on a flange-block *s'*, fitted to the flange of the I-beam and provided with 120 a horizontal surface at its top for receiving the surface *s*. The upper surface of the lower flange of each I-beam being almost invariably inclined considerably and the distance between I-beams varying sometimes as much 125 as one or two inches, it is clear that if the floor-block *r* rested directly upon the flanges of the I-beams the lower surface of the block *r* would lie either above or below its calculated level whenever the I-beams were closer together or farther apart, respectively, than had been calculated for. By means, however, of the flange-block *s'*, which fits the incline of the flange of the I-beam and presents a horizontal 130

resting-face for the surfaces of the block r , the variation in the distance between I-beams does not affect the setting of the block r at its proper height. Furthermore, the blocks r are formed slightly shorter than the distance between the webs of neighboring I-beams, and therefore the variation in the distance between I-beams would in some cases give too small a resting-surface for the floor-blocks r if the flange-blocks s' were not present. I compensate for the variation in the length of the blocks r and in the distance between neighboring beams by means of a fitting-piece having detachable parts scored or grooved, so as to readily knock off the surplus portion and enable the fitting-piece to accurately occupy any space which may be formed by the variation in the structure. Preferably the fitting-piece may be separate from the flange-block s' in the form of a wedge t , scored or grooved, so that its projecting point after it is inserted in place between the flange-block and the floor-block r may be broken off by the plasterers. In Fig. 17 the projecting end is shown ready to be broken off at the grooves or scores, (indicated by t' .) In Fig. 18 it is shown broken off and the ceiling-plaster y applied to finish the construction. The flange-block s' may be provided with the scored detachable portions s'' , one or more of which may be knocked off by the masons or workmen in fitting the flange-blocks s' to the floor-blocks r . Therefore the floor-block s' forms another fitting block or piece provided with portions detachable by means of the scores or grooves. While I have shown these two fitting-pieces s' and t , either one may of course be used without the other and may be used in floors of radically-different construction from that shown in Figs. 15 and 16.

It will be seen that the floor-block r , Figs. 15 and 16, is provided with a tension member l' at its base, extending parallel with the ceiling, turning up in the neighborhood of the I-beams and resting on the upper flanges, therefore contributing to the shearing strength of the block r . I also prefer to form the blocks r at the factory with the veneered lower surface, the veneer consisting of my fire and water resisting tiles x . When this is done, the blocks r consist of the load-supporting portion and the fire and water resisting veneer x , together with the irons l' , ready to be put in place in the floor construction. In placing them the flange-blocks s' are first applied to the lower flanges of the beams, knocking off as many of the detachable sections s'' as may be needed to allow for the lack of parallelism between the I-beams at different portions of the floor. The blocks r are then laid and the wedges t inserted laterally in the interval provided for them and pushed down to block the parts firmly together. Cement may be supplied to the various surfaces by masons or may be poured in, preferably filling in around the I-beams. A filling-block v may be used, as shown in Fig.

15. Where the block r is arched, as in Fig. 15, blocks w may be employed to support the floor and these preferably provided with notches to receive the floor-sleepers or floor construction, (shown at o' in Fig. 15.) The floor-blocks r in order to bear more directly upon the lower flanges of the I-beam and in order to be inserted readily in place should be longer than the distance between the lower flanges of neighboring I-beams and shorter than the distance between the webs of neighboring I-beams. When such construction is used with the filling-blocks v and w , a very light, strong, economical, and easily-laid construction is obtained.

Having now fully described my invention in its preferred embodiments, I claim and desire to secure by these Letters Patent the following:

1. In combination in fireproof construction and with the supports thereof, the complete and self-sustaining load-supporting body consisting largely of set-up materials and carried by the said supports, ceiling beneath the said load-supporting body, and a layer of non-corrosive fire and water resisting material of relatively greater fire and water resistance than and secured to and supported by the said load-supporting body, and to which the said ceiling is applied, the said layer of fire and water resisting material being entirely distinct from, but detachably secured to the said load-supporting body at surfaces or points for fracture, whereby it may be readily detached and replaced without injury to or disturbance of the said load-supporting body, substantially as set forth.

2. In combination with the supports, a load-supporting body of set-up materials carried by said supports, a layer of tile or burnt material secured and supported by and beneath the said load-supporting body, distinct therefrom but detachably secured thereto at a surface for fracture, and the ceiling beneath the said layer, substantially as set forth.

3. In combination with a load-supporting body of relatively low fire and water resistance, a non-supporting layer of relatively high fire and water resisting material distinct from the said load-sustaining body and secured thereto at surfaces or points for fracture, and a ceiling secured beneath the said non-supporting fire and water resisting layer, substantially as set forth.

4. In combination with a load-supporting body comprising blocks or large masses of material, a fire and water resisting layer consisting of blocks or masses of relatively small horizontal dimensions compared with the said load-supporting body, the said layer being secured by means of and beneath the said load-supporting body and detachable therefrom without injury to the said load-supporting body, substantially as set forth.

5. In combination as a means for supporting and fitting floor-blocks to I-beams or flanged supports, a flange-block fitting the

flange of said support, a floor-block cut away to partially inclose the said flange-block and rest upon it, and a fitting-piece interposed between the said floor-block and the said flange-block below the point where the said floor-block rests upon the said flange-block, substantially as set forth.

5 6. As an article of manufacture, a fitting-block for floor construction provided with one or more scored or recessed detachable projections, substantially as set forth.

10 7. A flange-block provided with a scored or grooved detachable projection, substantially as set forth.

15 8. A wedge-shaped fitting-block scored or grooved to form detachable portions, substantially as set forth.

9. A floor-block, *r*, comprising an upper load-sustaining body of set-up materials and

an under layer of burnt materials applied thereto and detachable therefrom at a plane or surface for fracture, substantially as set forth.

10. The floor-block having a transverse cross-section large at the upper part and at the base, but relatively small at the intermediate or web portion, and an iron bar embedded in the lower portion thereof, and extending upward and projecting from the said block at the end thereof, substantially as set forth.

20 25 In testimony whereof I have hereunto set my hand at New York, N. Y., this 17th day of August, 1897.

HOWARD CONSTABLE.
